UNITED STATES PATENT OFFICE.

CLARENCE W. NARY, OF CHICAGO, ILLINOIS, AND JAMES WEST, OF JAMAICA PLAIN, BOSTON, MASSACHUSETTS; SAID WEST ASSIGNOR TO EUGENE M. WEEKS, OF BOSTON, MASSACHUSETTS,

DEVICE FOR LINING UP PRESS FORMS.

Application filed April 18, 1922. Serial No. 555,021.

To all whom it may concern:

Be it known that we, CLARENCE W. NARY, a citizen of the United States, and resident of Chicago, county of Cook, State of Illinois, and JAMES WEST, a citizen of the United States, and resident of Jamaica Plain, Boston, county of Suffolk, Commonwealth of Massachusetts, have invented an Improvement in Devices for Lining Up Press Forms, of which the following description, in connection with the accompanying drawings, is a specification, like characters on the drawings representing like parts in each of the several views.

This invention relates to devices for the use of printers and more particularly for use in book printing or the like in which a number of pages are printed simultaneously upon a sheet which is afterwards folded and trimmed to produce the individual pages. In this class of work it is requisite that the type or plates for all the pages, which are thus assembled to be produced at once, be properly aligned and spaced with respect to each other in order that each page will be correctly printed, and all the pages show the same margin when trimmed. The principal object of the invention is to provide a simple, convenient and easily operated device or appliance adapted to be applied to a type frame or chase and equipped with means for lining up and squaring both the head and back or side margins of a multiplicity of page units in the chase simultaneously. A further object is to provide a device of the kind stated adapted to line up or square pages either of even or uneven sizes. A still further object is to provide a device of the kind stated adapted to line up and square quickly and accurately the page units in a chase whether the chase or iron frame in which the forms are locked be itself square and true or not, or whether the cross bars interiorly of the chase be true or not. The foregoing and other objects and advantages of the invention will more fully appear from the following detailed description taken in connection with the accompanying drawings, and the distinctive features of novelty will be pointed out in the appended claims.

Referring to the drawings:

Fig. 1 is a plan view of a device embody-

ing the invention with intermediate portions broken away;

Fig. 2 is a side elevation of a straight edge 55 and elements associated therewith employed in the invention, the mounting bar or track being shown in section on line 2—2 of Figure 1;

Fig. 3 is a transverse section on line 3—3 60 of Figure 1;

Fig. 4 is a relatively enlarged partial detail section on line 4—4 of Figure 1;

Fig. 5 is a relatively enlarged detail section on line 5—5 of Figure 1; and 65

Fig. 6 is a plan view illustrating the manner of use of the invention.

10 indicates a stout metallic bar of a length to extend across the chase or frame C which bear the page units P. This bar is shown as 70 oblong in cross section, being preferably about one-half inch wide and one inch deep. This bar 10 which constitutes a track on which the alining elements of the invention are adjustably fitted, has adjustably fitted to 75 its end portions clamping shoes or blocks 11. These shoes 11 which are alike at each end of the bar, are each equipped on their tops and intermediate the length thereof with a boss 12 having a squared passage receiving 80 and fitting the bar 10, these bosses being split at one side and equipped with clamping screws 13 passed through this split side and having handles 13^a, whereby the shoes may be clamped immovably in adjusted position 85 upon the bar 10. Each shoe 11 extends a substantial distance each way from the central boss 12 and has at its extremities bearing portions 14 adapted to engage the side 90 of the chase. Intermediate the length of the shoe and directly under the bar 10 the shoe is also provided with a clamping screw 15 having an operating head 15^a. The bar 10 is graduated toward each end thereof symmetrically from a central point. For securing the bar or track 10 in correct and accurate position upon the chase, the clamp screw 13 of one of the shoes being released, that shoe is slid along the bar until the contact points 14 of the shoe engage the side of the 100 chase with the zero point of the bar central of the chase. The shoe is then clamped to the bar and the shoe at the other end of the bar adjusted up against the chase so that its con-

95
100

tact points 14 engage therewith. Then the screws 15 are turned up to impinge against the chase, making a third contact point of the shoe with the chase and permitting the bar to be securely claimed to the chase. The bar or track 10 has slidably fitted thereon, a housing sleeve 16 which has fixed to the bottom thereof a straight edge bar or strip 17, which is thus held to extend precisely at right angles to the bar or track 10. This straight edge 17 has its opposite sides beveled as indicated at 17^a and graduated, usually in pica graduations. The passage through the sleeve 16 fits the bar 10 closely at its sides, but is provided with clearance as indicated at 16^a for a small vertical movement of the sleeve with the straight edge 17 which it bears, with respect to the bar. The sleeve 16 is normally held at its upper limit of movement with respect to the bar 10 so as to hold the straight edge 17 in a raised position where it will not touch the press forms as it is adjusted thereover. For this purpose I show presser plates 18 adjacent the ends of the sleeve, equipped with studs 18^a intermediate the length thereof and acted on by compression springs 19 surrounding the studs 18^a and housed in hollow bosses 20 at the top of the sleeve. For pressing the straight edge downward with respect to the bar 10 so as to bring it directly upon the tops of the press forms I provide means shown as a cam head 21 in the form of a yoke pivoted at 22 to a block 23 and having a projecting hand piece 21^a. The block 23 has fixed thereto bars or rods 24 extending downward at the sides of the sleeve and having fixed at their lower ends a cross piece 25 extending transversely under the bar 10 and having a range of movement in a recess 26 cut in the bottom and sides of the sleeve. It will be understood that when the cam head 21 is in the position shown in Figures 2 and 4, the straight edge 17 is elevated a small distance above the type forms, so that it may be slid along the bar 10, and when brought to position for alining the heads of a row of page units it may be pressed into close proximity to the page units by movement of the cam head. To facilitate locating the straight edge 17 exactly central of the length of track 10, or for its adjustment along the track predetermined measured distances, the top of the sleeve 16 is provided with window openings 27 directly over the edges of the straight edge, and the sides of these window openings may be provided with marks 27^a precisely alined vertically with the sides of the straight edge. The straight edge 17 thus adjustably mounted upon the track 10 provides means whereby the page units may be lined up conveniently and with precision as to the headings thereof. For alining the back or side margins of the page units by the same movements and adjustment, we provide one or

more fingers or markers 28 adjustably mounted upon the top of the straight edge 17. As shown herein there may be four of these fingers on each end portion of the straight edge, i. e. at each side of the central sleeve 16. These fingers or marker plates 28 are adjustably mounted upon rods 29 which are fixed at the top of the straight edge 17 intermediate the width thereof. The inner ends of these rods are shown as fixed in sockets 30 which may be formed as depending lugs at the sides of the sleeve 16, while the outer ends of the rods are fixed in heads 31 fixed at the ends of the straight edge. Each of the finger or marker members 28 is equipped with a bearing boss 32, which affords relatively extending bearing on the rod 29 and is equipped with a set screw 33 for securing it in adjusted position upon the rod. These bearing bosses are also made to fit the top of the straight edge as indicated at 32^a so that the fingers 28 are held for sliding movement on the straight edge and in accurate alinement at right angles to the edges of the straight edge. Thus as the straight edge 17 is slid along the track 10 the fingers 28, having been first alined with the sides of one set of press forms, will be brought successively opposite the other lines of press forms in the chase so that the back margins or sides of the press forms may all be brought in precise alinement. It will be noted that the device thus constituted is adapted to be applied to any size of form or chase within the length of the track 10, and that by reason of the spaced apart three point engagement of the shoes 11 with the sides of the chase, it may be correctly applied even though the chase or frame may be out of square. Likewise the device may be applied either to the center or other parts of the form as may be desired. The sleeve or housing 16 having the straight edge 17 securely fixed thereto and being itself of substantial length with a bearing fit upon the track 10 insures that the straight edge will always be perfectly rectangular with respect to the track, while the described mounting of the fingers 28 likewise insures that these fingers or markers will always extend precisely at right angles to the straight edge. We are aware that the invention may be embodied in other specific forms without departing from the spirit or essential attributes thereof, and we therefore desire the present embodiment to be considered in all respects as illustrative and not restrictive, reference being had to the appended claims rather than to the foregoing description to indicate the scope of the invention.

Having thus described our invention, what we claim as new and desire to secure by Letters Patent is:

1. A device for lining up and squaring

- press forms comprising a track equipped with adjustable means at its end portions for securing the same to a printing frame or chase to extend thereover in any required position of adjustment, a housing mounted for sliding movement on said track, and a straight edge member borne by said housing and extending at right angles to said track.
2. A device for lining up and squaring press forms comprising a track adapted to extend over the top of a printing frame or chase, and equipped with adjustable clamping shoes at its end portions for engaging the sides of the chase, a housing slidably adjustable upon said track, and a straight edge member secured midway of its length to the bottom of said housing, said housing equipped with means for raising and lowering the straight edge member with respect to the track.
3. A device of the kind described comprising a bar constituting a track adapted to extend over the top of a printing frame and equipped with adjustable shoes at its ends adapted to engage the sides of the frame, a housing mounted for sliding movement upon said bar, a straight edge member secured midway of its length to said housing, and alining members adjustably mounted upon said straight edge member and extending at right angles thereto.
4. A device of the kind described comprising a track equipped with adjustable means at its ends for engaging the sides of a printing frame, a housing slidably adjustable upon said track, a straight edge member secured midway of its length to said housing and extending at right angles to said track, said housing equipped with means for raising and lowering said straight edge member, and alining members adjustably mounted upon said straight edge member at each side of said track to extend in parallelism therewith and at right angles to said straight edge member.
5. A device of the kind described comprising a track adapted to extend over the top of a printing frame and equipped with means for securing it to the frame in any required adjusted position, and means borne by said track adjustable to line up and square both the head, and the back or side margins of a multiplicity of page units simultaneously.
6. A device of the kind described comprising a track adapted to extend over a printing frame with means for securing the same to the printing frame in any desired position of adjustment, means adjustable at the ends thereof for securing the same to printing frames of different sizes, a device adjustable upon said track and extending at right angles thereto for lining up page units in one direction, and means borne by said device and extending in parallelism with said track for lining up the page units simultaneously in another direction.
7. A device of the kind described comprising a bar constituting a track adapted to extend over the top of a printing frame and equipped with adjustable clamping means at its ends adapted to engage the sides of the printing frame at any selected part thereof, a housing mounted for sliding movement upon said bar, a straight edge member secured intermediate its length to said housing and alining members adjustably mounted upon said straight edge member and extending angularly with respect thereto.
8. A device for lining-up and squaring press forms comprising a track adapted to extend over the top of a printing frame or chase, and equipped with adjustable clamping means at its end portions for engaging detachably the sides of the chase at any selected points thereon, a housing slidably adjustable upon said track, and a straight edge member secured intermediate its length to said housing, said straight edge member equipped with provision for alining forms in the frame or chase.
9. A device of the kind described comprising a bar constituting a track adapted to extend over the top of a printing frame and equipped with adjustable shoes at its ends adapted to engage detachably the sides of the frame at any selected portion thereof, a straight edge member secured intermediate its length to said housing, and alining members adjustably mounted upon said straight edge member and extending at right angles thereto.

In testimony whereof, we have signed our names to this specification.

CLARENCE W. NARY.
JAMES WEST.
